US0D1054631S

(12) **United States Design Patent** (10) **Patent No.:** **US D1,054,631 S**
(45) **Date of Patent:** **** Dec. 17, 2024**

(54) **HELMET**

(71) Applicant: **HJC Corporation**, Yongin-si (KR)

(72) Inventor: **Jae Chul Lee**, Yongin-si (KR)

(73) Assignee: **Samsung Electronics Co., Ltd.**, Suwon-si (KR)

(**) Term: **15 Years**

(21) Appl. No.: **29/859,051**

(22) Filed: **Nov. 7, 2022**

(30) **Foreign Application Priority Data**

May 24, 2022 (KR) 30-2022-0020656

(51) **LOC (14) Cl.** **02-99**

(57) **CLAIM**

The ornamental design for a helmet, as shown and described.

DESCRIPTION

FIG. 1 is a front perspective view of a helmet showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a bottom rear perspective view thereof.

The broken lines in the figures depict portions of the helmet which form no part of the claimed design.

1 Claim, 8 Drawing Sheets
